UNITED STATES PATENT OFFICE.

ALBERT L. JENSEN, OF OAKLAND, CALIFORNIA, ASSIGNOR TO DOBLE STEAM MOTORS CORPORATION, OF WILMINGTON, DELAWARE, A CORPORATION OF DELAWARE.

STEAM-PIPE MOUNTING.

Application filed June 29, 1927. Serial No. 202,251.

My invention relates to a means for conducting steam from a boiler to an engine, especially in vehicles such as automobiles. Steam automobiles are usually constructed 5 with the boiler secured to the frame at the forward end thereof and the engine secured to the rear axle and attached to the rear portion of the frame so that it can have relative movement with respect thereto. A relatively long 10 steam pipe conducts steam from the boiler at the front end of the frame to the engine adjacent the rear of the frame. The movement of the engine with respect to the frame and also the vibration of the vehicle as it passes over 15 irregularities in the road both tend to set up vibrations in the steam pipe. These vibrations are often accentuated because of the length of the pipe so that the pipe has a tendency toward undue movement, sometimes 20 termed "whip". Excessive vibration or whip of the steam pipe not only is objectionable of itself but it also is likely to give rise to crystallization and breakage of the steam pipe.

An object of my invention is to provide a 25 means for overcoming whipping of the steam pipe.

Another object of my invention is to provide a means which will permit normal movement of the steam pipe but which will prevent 30 undue and destructive vibration thereof.

My invention possesses other advantageous features, some of which with the foregoing will be set forth at length in the following description where I shall outline in full that 35 form of the steam pipe mounting of my invention, which I have selected for illustration in the drawings accompanying and forming part of the present specification. In said drawings I have shown one form of steam pipe mounting embodying my invention, but it is to be understood that I do not limit myself to such form since the invention, as set forth in the claims, may be embodied in a plurality of forms.

45 In the drawings:

Fig. 1 shows in side elevation the steam pipe mounting of my invention as it is applied to a steam automobile, portions of the vehicle frame being shown in cross section.

50 Fig. 2 shows in plan the steam pipe mounting of my invention.

My invention preferably includes means for opposing the motion of a steam pipe connecting two points having relative movement, 55 in a sufficient amount to dampen out un-

wanted vibration or whipping, and permit normal movement of the pipe.

In the embodiment of my invention disclosed in the accompanying drawings, the vehicle comprises a frame made up of two side 60 rails 5 and intermediate cross members 6, 7, 8 and 9. The frame is supported on axles 11 and 12 thru the intermediary of springs 13 and 14. The rear springs 14 are preferably shackled at their rear ends and are secured to the frame at their front ends by means of spring bolts of the usual kind. The engine 16 for propelling the vehicle is preferably mounted between the frame and the axle. At its rear end the engine is supported by the 70 axle 12 while the front end is carried by a tube 17 connected thru ball joints 18 and 19 to the cross member 9 and to the front of the engine head. The engine is thereby partially supported by the frame and a large part of the 75 engine torque is taken by the frame, but most of the driving stresses are transmitted to the frame thru the springs 14. The engine is free to move a limited amount in all directions. 80

At the front end of the frame is mounted a boiler 21, which is of any type suitable as a source of steam. Steam from its source in the boiler 21 is conducted thru a steam pipe 22 to its terminal at the engine 16. Adjacent the 85 boiler the steam pipe is supported by a hanger 23 gripping the pipe and in turn supported by the intermediate cross member 7. Proximate its entry into the engine, the steam pipe is interrupted by an interposed ball joint 24 90 which is steam tight but preferably permits considerable motion between the engine 16 and the pipe. A large part of the relative movement between the engine and the frame is taken up by the ball joint without being 95 transmitted further along the steam pipe. Some of the movement is transmitted, however, and in order to allow for variations in length of the steam pipe, I preferably provide a loop 26 intermediate the ends of the pipe. 100 The loop may be substantially semi-circular in extent as shown, or can be of any desired contour to impart the desired axial flexibility to the pipe.

The length of the steam pipe 22 together 105 with the relative movement between the engine 16 and the boiler 21 tend toward excessive vibration or whipping of the pipe, especially during progress of the vehicle over rough roads. The whipping is in itself ob- 110

jectionable as it sets up secondary vibrations throughout the vehicle and in addition can cause crystallization and eventual breakage of the steam pipe or associated parts. In order to reduce to a nullity the whipping and also to support the steam pipe intermediate its point of issuance from the boiler and its point of attachment to the engine, I have provided a toggle including the two arms 27 and 28.

10 The arm 28 is preferably attached to an intermediate cross member 8 thru a connection 29 permitting free movement of the arm while the arm 27 is pivoted to a sleeve 31 15 clamped on the steam pipe 22. The knee or joint of the toggle is preferably frictionally held from free movement. This frictional binding is accomplished by means of a bolt 32 coincident with the pivotal axis of the knee and carrying a coil spring 33 confined between the arm 27 and a nut located on the end of the bolt. The circular contacting surfaces of the two arms are thereby pressed together with the requisite amount of force 20 and offer considerable frictional resistance to the movement of the toggle. This resistance can be readily adjusted by moving the nut upon the bolt. The toggle therefore not only serves as a support for the steam pipe, 25 but also offers sufficient resistance to the movement of the pipe so that the forces which ordinarily set up vibration and whipping are damped out before they effect that result. The value of the opposing friction necessary for dampening, however, is not 30 sufficiently great to prevent normal movement of the steam pipe and it is consequently sufficiently free to accommodate itself to the relative motion between the engine 16 35 and the boiler 21.

40 I claim:

1. A steam pipe mounting comprising a steam pipe relatively stationary at one end and adapted to vibrate at the other end, and means for frictionally restraining the vibration of said pipe.
2. A steam pipe mounting comprising a steam pipe adapted to have movement with respect to its support, and means permitting said movement and restraining whipping of said pipe.
3. A steam pipe mounting comprising a frame, a terminal for steam adapted to move with respect to said frame, a steam pipe constrained at one end to move with said frame

and constrained at the other end to move with said terminal, and a device connecting said frame and said steam pipe for restraining the motion of said pipe.

4. A steam pipe mounting comprising a frame, a terminal for steam adapted to vibrate with respect to said frame, a steam pipe constrained at one end to move with said frame and constrained at the other end to move with said terminal, and a frictionally bound toggle connecting said steam pipe to said frame.

5. A steam pipe mounting comprising a frame, a source of steam on said frame, a terminal for steam connected to said frame, a pipe connecting said source to said terminal, said pipe being subject to whipping, and means for restraining said pipe against whipping but permitting normal motion thereof.

6. A steam pipe mounting comprising a frame, a steam pipe adapted to move at one end with respect to said frame, and a frictionally bound toggle connecting said pipe to said frame.

7. A steam pipe mounting comprising a frame, a source of steam on said frame, a terminal for steam adapted to move with respect to said frame, a steam pipe connected to said source, and a ball joint connecting said pipe to said terminal.

8. A steam pipe mounting comprising a frame, a source of steam on said frame, a terminal for steam adapted to move with respect to said frame, a steam pipe connecting said source and said terminal, a ball joint interposed in said pipe between said source and said terminal, and a frictionally bound toggle connecting said pipe to said frame.

9. A steam pipe mounting comprising a frame, a steam boiler on said frame, a steam engine mounted to move with respect to said frame, a steam pipe connecting said boiler and said engine, said pipe having a loop intermediate its ends, a ball joint interposed in said steam pipe adjacent said engine and a frictionally bound toggle connecting an intermediate portion of said pipe to said frame.

10. A pipe mounting comprising a pipe relatively stationary at one end and adapted to vibrate at the other end, and means permitting said vibration and restraining whipping of said pipe.

In testimony whereof, I have hereunto set my hand.

ALBERT L. JENSEN.
